United States Patent

Des. 241,879

Patented Oct. 12, 1976

241,879

INFORMATION VENDING MACHINE

Wesley E. Swift, Sepulveda, Marc Schwartz, Sherman Oaks, and William D. Lewis, Pasadena, Calif., assignors to For-Play Manufacturers Corporation, Sun Valley, Calif.

Filed Nov. 4, 1974, Ser. No. 520,589

Term of patent 7 years

Int. Cl. D20—01

U.S. Cl. D52—3 R

FIG. 1

FIG. 4

FIG. 2

FIG. 3

FIG. 5

FIG. 6

FIG. 7

FIG. 1 is a right front perspective view of an information vending machine showing our new design;

FIG. 2 is a right side elevational view thereof;

FIG. 3 is a front elevational view thereof;

FIG. 4 is a top plan view thereof;

FIG. 5 is a left side elevational view thereof;

FIG. 6 is a rear elevational view thereof; and

FIG. 7 is a bottom plan view thereof.

We claim:

The ornamental design for an information vending machine, substantially as shown.
